UNITED STATES PATENT OFFICE

2,307,156

CARPET SWEEPER

Fred W. Pullen, Grand Rapids, Mich., assignor to
 Bissell Carpet Sweeper Co., Grand Rapids,
 Mich.

Application May 16, 1940, Serial No. 335,565

3 Claims. (Cl. 15—41)

This invention relates to improvements in carpet sweepers.

This invention relates to carpet sweepers and has for its objects:

First, to provide a new and improved carpet sweeper.

Second, to provide such a carpet sweeper in which stub axles are employed so that it is possible to eliminate through axles which extend through the casing and are in the way of litter swept up by the carpet sweeper.

Third, to provide such a sweeper in which the stub axles are resiliently held so that the wheels on them may bear against the brush hub and may resiliently support the carpet sweeper and in which the parallelism between the axles and the brush is maintained.

Other objects and advantages pertaining to details and economies of construction and operation will appear from the description to follow. The invention is defined in the claims. Preferred embodiments of my invention are illustrated in the accompanying drawing, in which:

Fig. 1 is an end view of a carpet sweeper embodying my invention.

Fig. 2 is a detail view in section on the line 2—2 of Fig. 1 with some of the parts shown in full lines.

Fig. 3 is a detail partial view showing the operation of my invention.

Fig. 4 is a view showing a modified form of my invention.

The carpet sweeper shown generally at 1 consists of a casing 2 having top 3, sides 4, ends 5 and supporting end bars 6.

The carpet sweeper is provided with a suitable handle 7 and with a brush 8 which extends through the casing and is provided with a brush hub 9 adapted to engage the wheels 10.

The wheels 10 are independently mounted in yokes 11 consisting of a bight 12 and arms 13 extending each side of the wheel 10 and connected by a wheel axle 14 on which the wheel is mounted by means of a ball bearing 15.

The wheel is resiliently urged against the brush hub and resiliently supports the casing by means of a short leaf spring 16, one end 17 of which is rigidly connected to the bight 12 of the yoke 11 and which extends substantially tangentially of the wheel 10 but with its transverse flat dimension parallel with the axle 14. The other end 18 of the spring 16 is rigidly connected to a bracket 19 which is rigidly mounted on the casing and which holds the transverse flat dimension of the end 18 parallel with the brush 9 so that the

axle 14 of the wheel is held parallel with the brush 9. The spring 16 is a short leaf spring and by rigidly mounting the ends, I reduce the torsional resiliency very materially so that parallelism between the axle 14 and the brush 9 may be maintained, although the spring is subject to transverse bending to permit the operation of the sweeper in the usual way. The spring is made of such strength that when so mounted the torsional movement is reduced to a minimum.

To assist in maintaining parallelism between the axle 14 and the brush 9 and to equalize the action of the wheels and to give the brush a more extensive downward movement than the case is given when pressure is applied thereto, I provide equalizing levers 20. These levers are mounted between their ends on pivot pins 21 supported on the bars 6 which form part of the case. One end 22 of each lever is pivoted to the yoke by means of a pivot pin 23. The other end 24 is pivotally connected to the brush by means of a slide 25 carrying a pivot pin 26. The slide 25 is slidably disposed in a slot 27 in the member 28 carried by the supporting bar 6.

The end of the yoke arm 13 is slotted at 29 so that relative movement longitudinally of the lever 20 between the lever 20 and the yoke 11 is possible. Similarly, the lever 20 is slotted at 30 where it is connected to the pivot pin 21, so that there can be relative movement longitudinally of the lever between the lever and the supporting bar 6. A similar slot 31 at the end 24 of the lever likewise permits relative movement longitudinally of the lever between the lever and the brush. By providing two slotted connections, I assure contact between the wheels and the brush hub at all times. The levers assist in maintaining parallelism between the axle 14 and the brush 9.

In Fig. 3, I show how the sweeper embodying my invention operates. In full lines I have shown the sweeper in its normal position when not in use. When pressure is applied to the casing tending to move it downwardly, toward the floor to the position shown in dotted lines, the spring 16 flexes to the dotted line position. The levers 20 also move to the dotted line position, carrying the brush to the dotted line position. The movement of the brush is greater than the movement of the case, which permits the sweeper to be used on a great variety of floor coverings from linoleum to high nap rugs.

By mounting the spring 16 rigidly at both ends and by providing it with sufficient torsional resistance, I maintain parallelism between the axle 14 and the brush 9. Heretofore such parallelism

has been extremely difficult to maintain. Ordinarily stub axle constructions have been impractical to a great extent because of the expensive construction required to maintain parallelism and because of the wear upon the parts of such construction. By my arrangement of the parts and the use of the spring 16 rigidly mounted at both ends, I maintain parallelism without any parts which can be subject to wear.

In Fig. 4, in place of the spring 16, I provide a spring 116 which is a flat leaf spring with a curve 132. The end 118 of the spring is rigidly fastened to a bracket 119 and the end 117 is rigidly fastened to the bight 112 of the yoke 111. The spring is resistant to torsion and the transverse bending permits proper functioning of the parts of the sweeper.

The terms and expressions which have been herein employed are used as terms of description and not of limitation. There is no intention in the use of such terms and expressions of excluding equivalents of the features shown and described. It is recognized that various modifications are possible within the scope of the invention claimed.

Having thus described my invention, what I claim as new and desire to secure by Letters Patent is:

1. In a carpet sweeper having a casing and a brush extending therethrough having a hub and floor wheels engaging said hub, the combination of an independent mounting for each floor wheel comprising a yoke having a bight and an arm extending each side of each wheel and having a wheel axle extending between said arms, a leaf spring of a strength to resist torsional movement in operation of the carpet sweeper for urging said wheel against said hub and for supporting said sweeper resiliently on said wheel and having one end rigidly fastened to the bight of said yoke and extending substantially tangentially of the wheel and with its transverse flat dimension parallel to said wheel axle, and means rigidly mounted on said casing rigidly connected to and holding the other end of said spring with its transverse flat dimension parallel to said brush whereby parallelism between said brush and said wheel axle is maintained, and a pair of equalizer arms each pivotally secured between its ends to said casing and having one end pivotally connected to said yoke and the other pivotally connected to said brush to maintain alignment between wheel axles and the brush, where-

5 by downward pressure on said casing to move it toward the floor will create more extensive downward movement of said brush and whereby said wheels will be equalized in their vertical movements, two of the pivotal connections of each lever permitting relative movement longitudinally between the lever and the part to which it is connected to permit contact between the wheels and the brush hub at all times.

10 2. In a carpet sweeper having a casing and a brush extending therethrough having a hub and floor wheels engaging said hub, the combination of an independent mounting for each floor wheel comprising a yoke having a bight and an arm extending each side of each wheel and having a wheel axle extending between said arms, a leaf spring of a strength to resist torsional movement in operation of the carpet sweeper for urging said wheel against said hub and for supporting said sweeper resiliently on said wheel and having one end rigidly fastened to the bight of said yoke and extending substantially tangentially of the wheel and with its transverse flat dimension parallel to said wheel axle, and means rigidly mounted on said casing rigidly connected to and holding the other end of said spring with its transverse flat dimension parallel to said brush whereby parallelism between said brush and said wheel axle is maintained.

15 25 3. In a carpet sweeper having a casing and a brush extending therethrough having a hub and floor wheels engaging said hub, the combination of an independent mounting for each floor wheel comprising a yoke having a bight and an arm extending each side of each wheel and having a wheel axle extending between said arms, and means for resiliently urging said wheels against said hub and for resiliently supporting said sweeper on said wheels and for maintaining parallelism between said wheel axles and said brush comprising a short leaf spring of a strength to resist torsional movement in operation of the carpet sweeper having one end rigidly fastened to the bight of said yoke and extending substantially tangentially of the wheel and with its transverse flat dimension parallel to said wheel axle, and means rigidly mounted on said casing rigidly connected to and holding the other end of said spring with its transverse flat dimension parallel to said brush, whereby torsional resiliency of said spring is substantially eliminated while permitting transverse bending thereof.
